UNITED STATES PATENT OFFICE.

ANTON M. VEDOE, OF QUINCY, MASSACHUSETTS.

REAMER.

1,424,268.

Specification of Letters Patent. Patented Aug. 1, 1922.

Application filed January 3, 1921. Serial No. 434,469.

To all whom it may concern:

Be it known that I, ANTON M. VEDOE, a subject of the King of Sweden, residing at Quincy, in the county of Norfolk and State 5 of Massachusetts, have invented an Improvement in Reamers, of which the following description, in connection with the accompanying drawings, is a specification, like characters on the drawings representing like

10 parts.

This invention relates to reamers, and more particularly to a sheet metal member having portions thereof bent to form integral reamer blades.

15 In the use of reamers in metal working, the cutting blades wear down and frequently nick or break, and, except in case of breakage, the reamer may be ground to sharpen the blades or obliterate the nicks. Such

20 grinding, however reduces the diameter of the tool so that thereafter it will not cut to the size for which it was originally intended. To obviate this, various constructions have been proposed by which the cutting diameter of the reamer may be adjusted, and

25 while these adjustable or expandable reamers are more or less satisfactory, they are relatively expensive to manufacture.

An important feature of the present invention, therefore, consists in providing an expandable reamer which may be quickly and inexpensively produced by forming the sleeve or active part of the reamer of sheet metal having portions thereof struck up to 30 form the reamer blades.

Another feature of the invention consists in means for firmly securing the sheet metal sleeve or active part of the reamer upon the body of the reamer.

40 Still another feature of the invention consists in striking-up the cutting blades in such a manner that they will be spirally disposed to increase the smoothness with which the reamer will cut.

45 The above, and other features of the invention will be clear from the following description in connection with the accompanying drawing, which shows one good practical form of the invention.

50 In the drawing:

Fig. 1 is a perspective view of an expandable reamer constructed in accordance with the invention, the greater portion of the reamer shank being broken away.

Fig. 2 is a longitudinal sectional view of 55 Fig. 1.

Fig. 3 is a sectional view taken on line 3-3 of Fig. 2.

Fig. 4 is a plan view showing the inner face of the sheet metal member which forms 60 the sleeve or active part of the reamer, the same being shown as it appears before it is bent to conform to the body of the reamer.

Fig. 5 is a transverse sectional view showing a modification of the invention. 65

The reamer illustrated has a shank 10 integral with the seat or body 11, upon which the sleeve or active part 12 of the reamer is mounted. The body 11 is preferably tapered towards its front end as shown in Fig. 2, 70 and the sleeve 12 is correspondingly tapered and is constructed to be expanded upon being forced along the tapered body 11, but this is not an essential feature of the invention since in certain constructions it may 75 be desirable to make the reamer non-expandable and to discard the sleeve 12 for a new one when it wears down or becomes dull.

The sleeve or active part 12 of the reamer is formed of sheet metal having sufficient 80 thickness to furnish the requisite strength and stiffness to the blades 13 which are struck up from the sheet metal. The sleeve 12 may be readily stamped out from sheet metal to form a blank as shown in Fig. 4. 85 In this view it will be noted that the upper and lower edges of the blank are not parallel but that they taper to the right, in order that when the blank is bent to conform to the body 11, it will form a tapered sleeve 90 as shown in Figs. 1 and 2.

The reamer blades 13 may be formed by producing slits 14 in the sheet metal blank extending generally transversely thereof and terminating short of the sides of the 95 blank, and the metal to one side of the slits is struck or bent up as shown. It is desirable that the cutting face of the reamer shall have the same diameter throughout a substantial portion of the sleeve 12, but since the sleeve, 100 in the embodiment shown, is tapered, it is necessary that the distance that each blade is struck up from the face of the sheet metal be increased as it approaches the front end of the reamer. This will be apparent 105 from the drawing where it will be seen that the blades 13 are bent up from the sleeve to a greater extent at b than at a. Bending

the blades up to a greater extent at one end thereof than at the other, has the desirable effect of giving the blades a slight spiral configuration as shown, since as a blade is raised, its cutting edge recedes from the plane of the slot 14. This spiral arrangement is desirable as it increases the smoothness with which the reamer will cut.

In order that the reamer may be expanded 10 from time to time as the same becomes worn, provision is made for adjusting the sleeve along the tapering body or seat 11. In the embodiment of the invention illustrated, the opposite ends of the body 11 are threaded as at 15 to receive correspondingly threaded nuts 16. These nuts engage the opposite ends of the sleeve 12, and by backing off one nut and tightening up the other, the sleeve may be forced along the body 11 to the desired position. The nuts 16 preferably serve 20 also to contract the sleeve into firm engagement with the body 11, and to this end, the inner face of the nuts 16 are undercut as at 17 to receive the correspondingly beveled ends of the sleeve 12 as clearly shown. The nuts 16 are preferably provided with flattened wrench receiving faces 18.

The sleeve 12 should be prevented from rotating about the body 11, and to this end, 30 in the present instance the body 11 has a longitudinally extending key-way 19 adapted to slidably receive a key 20 formed upon the blank or sleeve 12 by bending inwardly a marginal end portion of the blank as shown. The forward ends of the blades 13 are preferably tapered as at 21 in order that the reamer will readily enter the hole to be reamed.

In some embodiments of the invention it 40 may be desirable to form the sleeve or active portion 12 of the reamer from more than one sheet metal blank, and in Fig. 5 a modification is shown in which each sheet metal blank extends but half-way around the body 45 11 instead of substantially entirely around the body as in Figs. 1, 2 and 3. The construction shown in Fig. 5 differs from that shown in Figs. 1 to 4, in that the body 22 is provided with opposite key-ways, and each 50 curved blank 23 extends approximately half-way around the body 22 and has a key 24 entering one of the key-ways. In other respects the construction shown in Fig. 5 may be similar to that shown in Figs. 1 to 4.

55 By forming the sleeve or active part of the reamer of sheet metal which may be readily stamped out and bent to the desired configuration, the same may be quickly and inexpensively produced, and when the sleeve 60 becomes worn or dull, it may be readily removed and ground, and then adjusted upon the body 11 to the desired diameter. In some cases, due to the low cost at which the sleeve 12 can be produced, it may be desir- 65 able to discard the same for a new one when

it becomes dull or worn and not bother to grind it.

Claims:

1. A reamer comprising, in combination, a reamer body, a sleeve surrounding the body and formed of a sheet metal blank having portions struck-up transversely of the blank to form reamer cutting blades, the blank being bent lengthwise to convert it into a sleeve, and means for securing the sleeve upon the reamer body. 70

2. A reamer comprising, in combination, a reamer body, a sleeve surrounding the body and formed of a sheet metal blank having slits extending transversely of the blank and the metal cut by said slits being struck-up to form reamer cutting blades, the blank being bent lengthwise to convert it into a sleeve, and means for securing the sleeve 80 upon the reamer body. 85

3. A reamer comprising, in combination, a tapered reamer body, a sleeve having a tapered inner surface embracing the body and formed of a sheet metal blank having portions struck-up transversely of the blank to 90 form reamer cutting blades, the blank being bent lengthwise to convert it into a sleeve, and means for securing the sleeve adjustably upon the reamer body.

4. A reamer comprising, in combination, a 95 reamer body having a key-way extending lengthwise thereof, a sleeve surrounding the body and formed of a sheet metal blank having portions struck-up transversely of the blank to form reamer cutting blades and 100 having an end marginal edge bent inwardly to form a key entering the key-way, the blank being bent lengthwise to convert it into a sleeve, and means for securing the sleeve upon the reamer body. 105

5. A reamer comprising, in combination, a substantially cylindrical reamer body having a key-way extending lengthwise thereof, a cutter member upon the body formed of a sheet metal blank having portions struck-up 110 transversely of the blank to form reamer cutting blades and having an end marginal edge bent to form a key entering the key-way, the blank being bent lengthwise to conform to the curvature of said body, and 115 means for securing the cutter member upon the reamer body.

6. A reamer comprising, in combination, a substantially cylindrical reamer body, a cutter member upon the body formed of a sheet 120 metal blank having portions struck-up transversely of the blank to form reamer cutting blades, the blank being bent lengthwise to conform to the curvature of said body, and means for securing the cutter member 125 upon the reamer body.

7. A reamer comprising, in combination, a tapered reamer body, a sleeve tapered to conform to the taper of the body and formed of a sheet metal blank having slits extending 130

transversely of the blank, and the metal cut by said slits being raised an increasing distance along the length of the slits from the body of the sleeve and moved rearwardly as it is raised to form spiral cutting blades, the blank being bent lengthwise to convert it into a sleeve, and means for securing the sleeve upon the reamer body.

8. A reamer comprising, in combination, a reamer body, a sleeve surrounding the body and formed of a sheet metal blank having slits extending transversely of the blank but terminating short of the opposite sides of the blank and the metal cut by said slits being struck up to form reamer cutting blades,

the blank being bent lengthwise to convert it into a sleeve, and means for securing the sleeve upon the reamer body.

9. A reamer comprising, in combination, a substantially cylindrical reamer body, a sleeve formed of sheet metal bent to embrace the reamer body, the sleeve having slits extending longitudinally thereof and having the metal upon one side of the slits struck-up to form reamer cutting blades, and means for securing the sleeve upon the reamer body.

In testimony whereof, I have signed my name to this specification.

ANTON M. VEDOE.
